ELECTRIC SHAVER

John Oster, Racine, Wis., assignor to John Oster Manufacturing Company, Racine, Wis., a corporation of Wisconsin

Application March 31, 1939, Serial No. 265,244

6 Claims. (Cl. 30—43)

This invention relates to so-called electric shavers, and refers particularly to the shaving head thereof.

Nearly all of the many electric shavers now on the market are subject to the objection that they will not shave close, and that they are slow and require successive passes over the same area to obtain maximum effectiveness.

The present invention, therefore, has as one of its objects to provide an improved cutter head for power driven shavers, which makes possible closer shaving through a new method of cutting.

Another object of this invention is to provide a cutter head for electric shavers which is so effective that one stroke across a given area is sufficient to completely shave all hair therefrom.

Another object of this invention is to provide an electric shaver of the character described with novel means for detachably holding the cutter head properly positioned on the shaver and for maintaining the cutters under the correct amount of tension.

Another object of this invention is to provide a cutter head of the character described which is simple in design, and which is readily detachable from the body or supporting structure of the shaver.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein-disclosed invention may be made as come within the scope of the claims.

The accompanying drawings illustrate two complete examples of the physical embodiment of the invention constructed in accordance with the best modes so far devised for the practical application of the principles thereof, and in which:

Figure 1 is a side view of a shaver constructed in accordance with this invention, parts thereof being broken away and in section;

Figure 2 is a top plan view of the shaver with a portion of its housing broken away and in section;

Figure 3 is a perspective view showing the front end of the housing and the component parts of the cutter head, disassembled;

Figure 4 is a sectional view through Figure 1 on the plane of the line 4—4;

Figures 5 is an enlarged cross sectional view through the cutter head per se to illustrate the

manner in which the cutting action is effected; and

Figure 6 is an end view of the cutter head showing a modified embodiment thereof.

Referring now particularly to the accompanying drawings in which like numerals indicate like parts, the numeral 5 designates the housing or body of an electric shaver in which an electric motor (not shown) is housed. The drive shaft 6 of the motor projects into an oblong cavity or recess 7 in the front end of the body where it mounts an eccentric driving bushing 8. The eccentric driving bushing reciprocates the movable blade 9 of a cutter head 10 detachably mounted in the recess 7.

The cutter head, in addition to the blade 9, incorporates two stationary blades 11 between which the movable blade reciprocates. All of the blades have their outer edge portions provided with teeth, the teeth 12 on the movable blade being spaced farther apart than the teeth 13 on the stationary blades.

Any suitable manner of guiding the movable blade and maintaining it properly positioned with respect to the stationary blades may be employed, and in the present instance, the movable blade has two longitudinal ribs 14 on its opposite faces which ride in correspondingly shaped and positioned longitudinal grooves 15 in the inner faces of the stationary blades.

The meeting toothed outer edge portions of the stationary and movable blades are ground to fit accurately and effect a cutting action as the teeth on the movable blade pass the teeth of the stationary blades.

The three blades are held in proper assembled relation and in place in the cavity or recess 7 by a spring clip 16 secured in the bottom of the cavity or recess. The wings of this clip have ridges 17 on their outer extremities to snap into grooves 18 in the outer faces of the stationary blades when the assembled cutter head is properly positioned in the recess, at which time the inner edges of the stationary blades preferably engage the bottom wall of the clip, and the ends of the stationary blades contact end walls 19 struck up from the bottom wall of the clip.

The clip is secured in the cavity or recess 7 by screws or other suitable fastenings passing through holes 20 in the bottom wall of the clip and threaded into the adjacent portion of the body. A large hole in the bottom wall of the clip accommodates the eccentric driving bushing.

Reciprocal motion is imparted to the movable

blade by having the eccentric bushing engage in a recess 21 formed in the inner edge of the movable blade. While the movable blade has sufficient thickness to insure the edges of the recess 21 maintaining proper engagement with the eccentric bushing throughout its entire "throw," it need not be so thick that the bushing lies between the planes of its opposite faces at all positions, as the adjacent portions of the stationary blades can be cut away as shown.

In using the shaver, it is held in a position substantially perpendicular to the surface of the skin, as shown in Figure 4, and as a consequence, the area of the skin lying between the edges of the stationary blades is stretched and bulged outwardly. This action is permitted by virtue of the fact that the outer edge of the movable blade is spaced inwardly from the edges of the stationary blades and is preferably formed on an arc, as shown in exaggerated form in Figure 5.

Hence, the hair is caused to assume positions extending across the line of parting between the movable and stationary cutter blades as the shaver is moved across the surface of the skin, and as a result, the hair is cut off close to the surface of the skin during one sweep of the shaver.

As stated, the spaces between the teeth of the movable blade are wider than those of the stationary blades which act as combs. This affords more time for the hair to move into the spaces between the teeth of the movable blade, as will be readily apparent.

The teeth of the stationary blades are relatively narrow so there is small likelihood of a hair being held down and kept from being cut off as the shaver is moved across the skin, but to completely guard against this possibility, the teeth on one movable blade may be staggered with respect to those on the other stationary blade, as shown in Figure 6. With this arrangement, any hair held down by the teeth of one blade will be aligned with the spaces of the other blade to enter the same upon the return stroke of the shaver.

To remove the cutter head, it is only necessary to grip the same at the ends of its stationary blades and apply a smart outward pull, the spring clip 16 being of such strength as to yield and release the cutter head in response to such a pull, although under all ordinary circumstances, the tension of the clip is sufficient to hold the head in place.

From the foregoing description taken in connection with the accompanying drawings, it will be readily apparent that this invention provides a substantial improvement in so-called electric shavers through the use of a spring clip for the cutter head which in addition to detachably maintaining the cutting head assembled and under spring tension, also holds the stationary guards or comb members against movement during reciprocation of the movable cutter.

What I claim as my invention is:

1. In a shaver of the character described: a movable cutting blade having a toothed edge portion; toothed guards overlying the opposite side faces of the movable cutting blade, said toothed guards having shoulders on their outer faces between and parallel to their outer toothed edges and their inner edges; and a spring member disposed over the inner edges of the toothed guards and having a substantially U-shaped cross section to provide resilient side walls engageable with the shoulders on the toothed guards to detachably maintain the guards and the movable cutting blade assembled as a unit and exerting an inward clamping force on the guards so as to provide the tension necessary for proper cutting action at opposite sides of the movable cutting blade.
2. In a shaver of the character described: a movable cutting blade having a toothed edge portion; toothed guards overlying the opposite side faces of the movable cutting blade and cooperating therewith to provide a cutting head having cutting edges at opposite sides of the movable cutting blade; a spring clip having a substantially U-shaped cross section so as to provide spaced resilient side walls for embracing the inner end of the cutting head to thereby maintain the cutting edges thereof under spring tension; and interengaging means on said side walls and the adjacent faces of the toothed guards maintained operative by the resiliency of said side walls for releasably holding the cutting head assembled with respect to the spring clip.
3. In a shaver of the character described: a movable cutting blade having a toothed edge portion; toothed guards overlying the opposite side faces of the movable cutting blade and cooperating therewith to provide a cutting head having cutting edges at opposite sides of the movable cutting blade; a spring clip having a substantially U-shaped cross section so as to provide spaced resilient side walls for embracing the inner end of the cutting head to thereby maintain the cutting edges thereof under spring tension; interengaging means on said side walls and the adjacent faces of the toothed guards maintained operative by the resiliency of said side walls for releasably holding the cutting head assembled with respect to the spring clip; and end abutments on the spring clip cooperating with the resilient side walls thereof to hold the toothed guards stationary during movement of the movable cutting blade.
4. In a shaver of the character described: a cutting head comprising a pair of spaced apart comb members having shoulders on their outer faces between and parallel to their outer toothed edges and their inner edges, and a movable cutter member reciprocable between said comb members and having teeth on its outer edge cooperating with the teeth of the comb members to provide cutting edges at opposite sides of the movable cutter member; means for detachably securing the cutting head members assembled and in cutting relationship comprising, a part having a bottom wall engaged with and overlying the inner edges of the comb members; and spaced apart resilient side walls extending up from the bottom wall of said part to resiliently clamp the cutting head therebetween, said resilient side walls being arranged to engage and exert an inward and downward force on the shoulders of the comb members so as to maintain the cutting head engaged with the bottom wall of said part and the movable cutter member clamped under tension between the comb members.
5. In a shaver of the character described: a cutting head comprising a pair of spaced apart comb members having shoulders on their outer faces between and parallel to their outer toothed edges and their inner edges, and a movable cutter member reciprocable between said comb members and having teeth on its outer edge cooperating with the teeth of the comb members to provide cutting edges at opposite sides of the movable cutter member; means for detachably

securing the cutting head members assembled and in cutting relationship comprising, a part having a bottom wall engaged with and overlying the inner edges of the comb members; spaced apart resilient side walls extending up from the bottom wall of said part to resiliently clamp the cutting head therebetween, said resilient side walls being arranged to engage and exert an inward and downward force on the shoulders of the comb members so as to maintain the cutting head engaged with the bottom wall of said part and the movable cutter member clamped under tension between the comb members; and end abutments on said part engaging the opposite ends of the comb members and cooperating with the resilient side walls to hold the comb members stationary with respect to the movable cutter member during reciprocation thereof.

6. In a shaver of the character described: a 20 movable cutter; comb members disposed flatwise against opposite sides of the movable cutter;

teeth on the movable cutter cooperating with the teeth of the comb members to provide a cutting area at opposite sides of the movable cutter; a readily separable connection between the comb members and the movable cutter operable to guide the movable cutter for reciprocal motion between the comb members; and a single spring clip having resilient side walls arranged to contact the outside faces of the comb members at points adjacent to said connection so as to maintain said connection between the movable cutter and the comb members operative whereby the movable cutter and the comb members are maintained in cutting relationship with the necessary tension at the cutting areas; and a detent connection between said resilient side walls and the outer faces of the comb members for detachably maintaining the comb members and movable cutter assembled as a unit with the clip.

JOHN OSTER.
